DISPLAY UNIT

Carl B. Holm, Englewood, N. J., assignor to International Braid Company, a corporation of Massachusetts

Application August 6, 1941, Serial No. 405,612

4 Claims. (Cl. 206—44)

This invention relates to a display package such, for instance, as may contain a plurality of different articles to be exhibited on the counter for purchase.

In the sale of some articles such, for instance, as shoe laces, these may be sold in boxes of rather large numbers and if one desires to purchase for re-sale less than the complete box, he has no convenient manner of displaying the same.

One of the objects of this invention is to provide a smaller package of the articles to be displayed which package may be taken from the larger container and this smaller package then present by itself a display for prominently bringing to the eye the merchandise contained therein.

Another object of this invention is to provide an arrangement so that when the package is so utilized, additional display material may be provided by extending or sliding the parts of the container to expose additional surface which may contain advertising or something to attract the eye.

Another object of this invention is to provide an easel-like display and utilize the formation of the easel arrangement for retaining the slidable member in raised position.

Another object of the invention is to provide a construction which may be readily folded from sheet stock such as cardboard and obtain the various advantages by manipulations of sheet stock with a minimum amount of fastenings or additional assembly operations.

With these and other objects in view, the invention consists of certain novel features of construction, as will be more fully described, and particularly pointed out in the appended claims.

In the accompanying drawings:

Fig. 1 is a perspective view of the display package;

Fig. 2 is a perspective view looking at the back side thereof with the easel in position and the slidable member moved upwardly as shown in Fig. 1;

Fig. 3 is a fragmental perspective view illustrating the securing of the article-containing portion of the package in its assembled position;

Fig. 4 is an edge view, partly in section, illustrating the relatively movable parts;

Fig. 5 is a perspective view of the slidable member;

Fig. 6 is a perspective view of the back wall and front wall before folding; and

Fig. 7 is a central sectional view of the device complete and in contracted position ready for positioning in a larger package.

The unit of this invention is intended to be a part of a larger package but which may be itself utilized as a display of a smaller number of articles, and when in such use an easel-like member is provided with the easel locked in position and with a member which may be slid out to additionally expose some attractive or advertising material thereon.

With reference to the drawings, I have illustrated the package in a form which will contain shoe laces, although other articles might equally well be displayed. The package consists of a back wall designated 10, and as shown in Fig. 6, is formed from a sheet of cardboard stock with flanges or side walls 11 bent up at either edge thereof. The front wall is designated 12 and is much shorter and also is provided with flanges or side walls 13. A bottom wall 14 is also formed and is joined to the back wall by a fold 15 and to the front wall by a fold 16. These walls are folded into position as shown in Fig. 1. The side walls 11 and 13 are joined by staple 17 (see Fig. 7) to hold the back, front and side walls in the assembled relation shown in Figs. 1 and 7.

By folding the sheet stock and assembling it in this manner, a pocket 18 is provided for the reception of articles 19 of merchandise which I have shown as individual pairs of shoe laces suitably assembled by banding and which stand upwardly from the pocket so as to cause their major portion to be displayed.

A front wall 20 of some transparent material may also be provided to assist in protecting the banded pairs of laces or other articles so packaged.

An easel member 21 is formed by cutting the back wall 10 along the lines 22, 23, and 24 and folding the stock so slit along the line 25 to provide this easel member and to leave an opening 26 in the back wall 10. In order to lock this easel member 21 in position, the easel is cut out to provide a recess 27 (see Fig. 4 or Fig. 7) and the stock of the back wall 10 is further cut along the line 28 somewhat in the shape of the upper portion of a heart and folded along the line 29 to provide lock 30 so that the heart-shaped notch 30 will enter a cut-out recess 31 in the easel which is shown in engagement in Figs. 2 and 4 whereby to lock this easel in position. When the package is made of a material having normal resiliency, there will be a limited tendency of the member 21 when in locked position to move toward its initial position which will be sufficient to move the locking member therewith a distance 55 to extend the portion 31a thereon, formed in pro-

viding the notch 31, through the opening 26 and forwardly of the wall 10, or this member 21 may be manually moved sufficiently to extend the portion 31a through the opening 26 as shown in Fig. 2.

Along the forward surface of the back wall 10, I have provided a slideable member 32 which is of a size substantially the width of the back wall 10 and of a size of nearly the height of the back wall 10. This member is shown alone in Fig. 5. This member 32 is cut, and a tab 33 is pushed rearwardly from the stock of this member and passed through the opening 26 so as to lie along the rear surface of the back wall 10 to provide a handle by which this member may be readily engaged so that the member 32 may be slid upwardly with reference to the back wall 10 from the position shown in Fig. 7 to the position shown in Figs. 1, 2, and 4. In order to assist this manipulation a hole 34 is provided for the insertion of some sharp pointed instrument if desired.

The lower edge 35 of this member 32, when in its raised position, will rest upon the part 31a of the locking member 36 so as to hold the slideable member 32 in raised position. A notch 37 is formed in the lower edge of this member 32 so as to receive this part 31a of the locking member and by the depth of this notch the height at which the member 32 will be retained in raised position will be determined. The upper portion 38 of this member 32 as shown in Fig. 1 on its forward face may carry advertising display or some printed matter to attract attention to the merchandise 19 which is contained in the forward side of the package.

I claim:

1. A display package comprising a back wall with means extending forwardly thereof for containing merchandise, a portion of said wall being foldable rearwardly to provide an easel and leave an opening in said wall, and a display member of generally the size and shape of said wall loosely resting against the forward side of said wall provided with a tab fixed thereto and extending through said opening and along and in frictional engagement with the rear side of the wall to hold the member against the wall and providing a handle for said member to slidably move the same upwardly beyond the upper edge

of said wall to expose its upper portion for display.

2. A display package comprising a back wall with means extending forwardly thereof for containing merchandise, a portion of said wall being foldable rearwardly to provide an easel and leave an opening in said wall, and a display member of generally the size and shape of said wall loosely resting against the forward side of said wall provided with a tab cut from the stock thereof extending through said opening and along and in frictional engagement with the rear side of the wall to hold the member against the wall and providing a handle for said member to slidably move the same upwardly beyond the upper edge of said wall to expose its upper portion for display.

3. A display package comprising a back wall with means extending forwardly thereof for containing merchandise, an easel foldable rearwardly from said wall and leaving an opening therein, a locking member also foldable from said wall into engagement with said easel and with a portion thereof extending through said opening and forward of said wall, and a member on the forward side of said wall inclosed within said package and slideable upwardly beyond the upper edge of said wall to expose its upper portion for display, said slideable member when in its upper position resting on the said portion of the locking member extending through said opening to be supported thereby in raised position.

4. A display package comprising a back wall with means extending forwardly thereof for containing merchandise, an easel foldable rearwardly from said wall and leaving an opening therein, a locking member also foldable from said wall into engagement with said easel and having a portion thereof extending through said opening, a member on the forward side of said wall provided with a tab extending through said opening providing a handle for said member to slidably move the same upwardly beyond the upper edge of said wall to expose its upper portion for display, said slideable member having a notch to receive the said portion of the locking member extending through said opening to rest thereon to be supported thereby in raised position.
